FINGERNAIL BRUSH

Max R. Milarch, Portland, Oreg.

Application October 4, 1938, Serial No. 233,285

1 Claim. (Cl. 15—167)

This invention relates generally to brushes, and particularly to a fingernail brush.

The main object of this invention is to construct a brush by means of which the fingernails may be quickly and easily cleaned without discomfort or injury to the fingers.

The second object is to construct a brush of the class described which will be easy to manufacture and which will be adaptable to large or small fingernails.

These and other objects are accomplished in the manner set forth in the following specification as illustrated in the accompanying drawing, in which:

15 Fig. 1 is a perspective view of one form of the device.

Fig. 2 is a longitudinal section taken along the line 2—2 in Fig. 1.

20 Fig. 3 is a side elevation of a modified form of the device, a portion of which is broken away in section.

Fig. 4 is a section taken along the line 4—4 in Figs. 2 and 3.

25 Fig. 5 is a side elevation showing the device in actual use.

Similar numerals refer to similar parts throughout the several views.

Referring in detail to the drawing, there is shown an inner tube 10 which is surrounded by a plurality of bristles 11 outside of which is placed an outer tube 12. The tubes are made of metal or other suitable material. The tube ends 13 and 14 are flared outwardly for the purpose of causing the bristle ends 15 to flare away from the longitudinal axis of the brush.

It is desirable to provide a knurled surface 16 around the outside of the tube 12.

In the form of the device shown in Figs. 3 to 5 the inner tube 17 is surrounded by the bristles 18 which in turn are enclosed within 5 the thimble shaped shell 19 whose end 20 is closed and whose intermediate portion 21 is knurled. In this form of the device the bristles 18 also flare outwardly. The tube 17 is held within the shell 19 by forming a bead 22 within 10 same.

In the operation of either form of this device, the tip of the finger 23 whose nail 24 is to be cleaned is placed against the hollow brush and as shown in Fig. 5 the brush is then rotated by 15 means of the other hand causing the bristles 11, 15 or 18 to clean the outermost edge 25 of the nail 24 which is nearest the finger 23. The brush can be rotated in either direction or in 20 one direction until the fingernail is thoroughly clean.

The advantage of making the device double ended in which the bristles 14 and 15 are of different diameters is to better adapt the device 25 to various sizes of fingers and fingernails.

I claim:

A fingernail brush consisting of a pair of telescopic metal shells of substantially uniform length concentrically spaced from each other and having a circular row of bristles occupying 30 the annular space between said shells, one end of said shells being flared outwardly in a manner to cause said bristles to flare outwardly.
